US0D1045977S

(12) **United States Design Patent** (10) Patent No.: **US D1,045,977 S**
(45) Date of Patent: ** Oct. 8, 2024

(54) **BARCODE PRINTER**

(71) Applicant: **Zhuhai Pantum Electronics Co., Ltd.**,
Zhuhai (CN)

(72) Inventors: **Chenglong Kang**, Guangdong (CN);
Yifan Zhao, Guangdong (CN); **Meijun Huang**, Guangdong (CN); **Ziyan Mo**, Guangdong (CN); **Xuan Wang**, Guangdong (CN); **Junkang He**, Guangdong (CN)

(**) Term: **15 Years**

(21) Appl. No.: **35/516,465**

(22) Filed: **Dec. 7, 2022**

(80) **Hague Agreement Data**

Int. Filing Date: **Dec. 7, 2022**

Int. Reg. No.: **DM/226888**

Int. Reg. Date: **Dec. 7, 2022**

Int. Reg. Pub. Date: **Mar. 3, 2023**

(30) **Foreign Application Priority Data**

Jun. 7, 2022 (CN) 202230343131.5

CLAIM

The ornamental design for a barcode printer, as shown and described.

DESCRIPTION

1. Barcode printer
2. Barcode printer
- 1.1 : Front
- 1.2 : Back
- 1.3 : Left
- 1.4 : Right
- 1.5 : Top
- 1.6 : Perspective
- 2.1 : Front
- 2.2 : Back
- 2.3 : Left
- 2.4 : Right
- 2.5 : Top
- 2.6 : Perspective

Designs 1-2 are used as barcode printers for printing; the bottom views of designs 1-2 are omitted since the bottom surfaces of the products are not easily visible or not visible in use; the broken lines represent portions of the article that form no part of the claimed design.

1 Claim, 12 Drawing Sheets
